(57) **CLAIM**

The ornamental design for a three compartment eyeglasses holder, substantially as shown and described.

DESCRIPTION

FIG. 1 is a top perspective view of the three compartment eyeglasses holder of the present invention shown with the compartments collapsed and flaps closed;

FIG. 2 is a front elevation view thereof;

FIG. 3 is a rear elevation view thereof;

FIG. 4 is an elevation view of the left side thereof;

FIG. 5 is an elevation view of the right side thereof;

FIG. 6 is a top plan view thereof;

FIG. 7 is a bottom plan view thereof;

FIG. 8 is bottom perspective view thereof showing the flaps open;

FIG. 9 is a top perspective view thereof showing the compartments expanded and flaps closed;

FIG. 10 is a top plan view thereof showing the compartments expanded and flaps closed;

FIG. 11 is bottom plan view thereof showing the compartments expanded and flaps closed;

FIG. 12 is a bottom perspective view thereof showing the compartments expanded and flaps open; and,

FIG. 13 is an elevation view of the left side thereof showing the compartments expanded and flaps open.

1 Claim, 10 Drawing Sheets
